US0D1001273S

(12) **United States Design Patent** (10) **Patent No.:** **US D1,001,273 S**
(45) **Date of Patent:** **** Oct. 10, 2023**

(54) **EAR CLEANER**

(71) Applicant: **HEIFENG ZHIZAO (SHENZHEN)
TECHNOLOGY CO., LTD**, Shenzhen
(CN)

(72) Inventors: **Di Wen**, Shenzhen (CN); **Hong Xin**,
Shenzhen (CN)

(73) Assignee: **HEIFENG ZHIZAO (SHENZHEN)
TECHNOLOGY CO., LTD**, Shenzhen
(CN)

(**) Term: **15 Years**

(21) Appl. No.: **29/857,971**

(22) Filed: **Oct. 26, 2022**

(30) **Foreign Application Priority Data**

Jul. 22, 2022 (CN) 202230471022.1

Primary Examiner — Samantha Q Lawrence

(57) **CLAIM**

The ornamental design for an ear cleaner, as shown and described.

DESCRIPTION

FIG. 1 is a perspective view of an ear cleaner showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the ear cleaner; and,

FIG. 10 is an enlarged view of portion 10 shown in FIG. 1. The dash-dash broken lines in the drawings depict portions of the ear cleaner that form no part of the claimed design. The dot-dash broken lines represent the boundary of the enlarged portion and form no part of the claimed design.

1 Claim, 10 Drawing Sheets
